CLAIM

The ornamental design for a radiation shield base, as shown and described.

DESCRIPTION

FIG. 1 is a top right side perspective view of a radiation shield base, according to the present invention;

FIG. 2 is a front elevation view of the radiation shield base of FIG. 1;

FIG. 3 is a back elevation view of the radiation shield base of FIG. 1;

FIG. 4 is a left side elevation view of the radiation shield base of FIG. 1;

FIG. 5 is a right side elevation view of the radiation shield base of FIG. 1;

FIG. 6 is a top plan view of the radiation shield base of FIG. 1;

FIG. 7 is bottom view of the radiation shield base of FIG. 1; and,

FIG. 8 is a top right side perspective view of the radiation shield base of FIG. 1, with the radiation shield housing illustrated, for context, in broken lines.

Broken lines, where present, illustrate portions of the radiation shield base that form no part of the claimed design.

1 Claim, 4 Drawing Sheets
